CLAIM

We claim the ornamental design for the channel fastener clip, as shown and described.

DESCRIPTION

FIG. 1 is a perspective view of the channel fastener clip attached to a channeled frame member such as a beam or post;

FIG. 2 is a perspective view of the channel fastener clip of FIG. 1 shown in isolation;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The evenly-spaced dashed lines illustrate environment and portions of the channel fastener clip, that do not form part of the claimed design.

1 Claim, 5 Drawing Sheets
